PHOTOGRAPHIC SHUTTER

Árpád Barényi, Berlin-Lichterfelde, Germany,
assignor to Voigtländer & Sohn Aktiengesellschaft, Brunswick, Germany, a joint-stock company of Germany

Application November 21, 1934, Serial No. 754,062
In Germany November 23, 1933

8 Claims. (Cl. 95—63)

My invention relates to improvements in photographic shutters, and the object of the improvement is to provide a shutter which is simple in construction and reliable in operation. With this object in view between a member such as a rotary ring for directly operating the blades and a hand operated device for imparting movement to said operating member an intermediate member is provided which is adapted to be directly engaged by the said hand operated device for opening the shutter, a latch being provided by means of which the said intermediate member may be locked in position for opening the shutter, and being adapted to be directly engaged by the said hand operated device, upon a second operation thereof, for releasing the intermediate member and permitting the same to close the shutter. Another object of the improvements is to provide a shutter in which the said intermediate member controlled by the hand operated device may also be used for releasing the motor or master member.

Thus in my improved shutter mechanism the said intermediate member and its hand operated device may be used for making time exposures, in which case the said latch is in operative position, or ball exposures in which case the said latch is made inoperative, and it may also be used for making instantaneous exposures.

For the purpose of explaining the invention an example embodying the same has been shown in the accompanying drawings in which the same reference characters have been used in all the views to indicate corresponding parts. In said drawings,

Fig. 1 is a fragmentary elevation showing a part of the shutter, the front plate and other parts being removed for clearly showing the mechanism,

Fig. 2 is a similar elevation showing the parts in the positions after the first operation of the hand operated device, the intermediate member being locked by its latch for making a time exposure,

Fig. 3 is an elevation similar to the one illustrated in Figs. 1 and 2 and showing the hand operated device at the end of the first operation and in initial position and ready for a second operation for moving the latch away from the intermediate member,

Fig. 4 is a similar elevation showing the hand operated device in engagement with the said latch and about to retract the same from the intermediate member,

Fig. 5 is a fragmentary elevation similar to

the one illustrated in Figs. 1 to 4, and showing in addition the means connecting the intermediate member with the pawl controlling the movement of the motor or master member, the said intermediate member being out of engagement with the blade operating member and in engagement with the said pawl of the motor or master member, and the hand operated device being in engagement with the intermediate member and about to operate the same for releasing the motor or master member.

Fig. 6 is a similar elevation showing in addition a hand operated cam ring, controlling the intermediate member, its latch, and a link connecting the motor or master member with the blade operating member,

Fig. 7 is a sectional elevation taken on the line 7—7 of Fig. 6, and

Fig. 8 is an elevation viewed in the direction of the arrows 8—8 the side wall of the shutter 20 casing being removed.

In the figures I have shown a shutter of the pivoted blade symmetrical opening type.

The shutter comprises the usual annular casing 1 having an exposure or lens opening 2 normally closed by blades 3, the said blades being confined between the rear wall 4 of the casing and a partition member 5 upon which latter most of the shutter operating mechanism hereinafter described is carried. Each of the blades is mounted on a pivot bolt 6, and it is provided with a slot 7 engaged by a pin 8 secured to an annular operating member 9. Thus, the blades 3 are opened and closed by reciprocating rotary movement imparted to the member 9, as is known in the art. At its front side the shutter casing is closed by an annular plate 47.

At a part of its circumference the operating member 9 carries a toothed segment 10, which is fixed thereto by a pin 11, and which is in engagement with teeth 12 of a disk 13 which is mounted on a pivot bolt 14. The disk 13 is acted upon by a coiled spring 34 tending to turn the same in a direction for closing the shutter, and it is adapted to be turned in opposition to the said spring by a hand operated device comprising a cylinder 15 secured to the partition member 5, a plunger 16 and a rod 17. The bottom 18 of the said cylinder is formed with the usual inwardly tapering and screw-threaded bore 19 adapted to have the usual ball or Bowden cable secured thereto, and it is formed with a bore 20 through which the wire of the Bowden cable is connected with the bottom of the plunger 16. In the construction shown in the figures the cylinder

der is formed with a longitudinal slot 21 for the passage of a pin 22 fixed to the bottom of the plunger 16 for direct operation thereof. At its inner end the rod 17 is made integral with a disk 23 bearing on the inner face of the bottom of the plunger for holding the rod axially of the cylinder 15. Between the said disk and a head 24 secured to the end of the cylinder 15 a coiled spring 33 is interposed which tends to force the plunger 16 inwardly and to place the disk 23 close on the bottom, so that the rod 17 is located axially of the cylinder. But the spring permits the rod 17 to be moved outwardly and inwardly and towards the center of the shutter, the head 24 being provided with a slot 25 permitting such displacement. The disk 13 is formed with a forwardly directed concave arm 26 which is normally located in position for engagement with the rod 17, so that the disk is turned anti-clockwise by outward movement of the plunger 16 and the rod 17, and when the disk is thus turned the rod 17 is slightly tilted inwardly, as is shown in Fig. 2.

Near the disk 13 a latch 27 is mounted on a pivot bolt 28 fixed to the partition member 4, and the said latch is formed with a nose 29 adapted to engage a nose 30 formed on the disk 13, and the said noses are located so that the latch is adapted to lock the disk 13 in the position to which it has been turned by the rod 17 being forced outwardly. A spring 31 tends to force the latch 27 into locking engagement with the disk 13. At its end the latch 27 is formed with a forwardly directed concave arm 32 similar in shape to the arm 26, and when the latch is in locking position the said arm 32 is in position for being engaged by the end of the rod 17 being forced outwardly.

On the partition member 4 a motor or master member 35 of any known or preferred construction is mounted. The construction of the said motor or master member is known in the art, and therefore I deem it not necessary to describe the same in detail. It has been described in the patent of the United States No. 1,856,308 granted to me May 3, 1932. By means of the said motor or master member instantaneous exposures may be made, and for regulating the time of the exposure the motor or master member is provided with any known or preferred retarding devices. Such retarding devices have not been shown in the figures, because they are known in the art and do not form a part of my present invention.

The spring housing of the said motor or master member is formed with an eccentric disk 36 on which a link 37 is mounted. The said link is adapted to be connected with the ring 9, and for this purpose it is formed with a notch 38 adapted to engage a pin 39 fixed to the member 9, a spring 40 tending to hold the link and the member 9 in engagement with each other.

The motor or master member 35 is adapted to be locked in position by means of a pawl 41 pivotally mounted at 42 and engaging a shoulder 43 of the housing of the motor or master member. The said pawl is made integral with a rear extension 44 formed with a toothed portion 45 located in position for engagement with the teeth of a disk 46 connected with the disk 13 the said parts being arranged so that by anti-clockwise rotary movement of the disk 46 the rear extension 44 of the pawl 41 is moved in a direction for releasing the motor or master member.

As is shown in Fig. 5, the pivot bolt 14 of the

disks 13, 46 is not directly fixed to the partition member 5, but it is mounted on a pair of links 50 mounted on the pivot bolt 28. Thus the said disks may be set into positions either for engagement with the operating member 9 or with the teeth 45 of the pawl 41, the spring 34 tending to throw the disk out of engagement with the operating member 9 and into engagement with the toothed portion 45. Further, the latch 27 is adapted to be locked in position against the action of the spring 31 so that it is not able to get into locking engagement with the disk 13. For this purpose a cam ring 51 is provided circumferentially of the lens opening 2, and the said ring is formed with a hook shaped portion 52 embracing an axial extension 53 of the pivot bolt 14 and formed at its end with a cam face 54. Further it is formed with a concentric slot 55 having an enlarged end portion 56 providing a cam 57, a pin 58 carried by a heel 59 of the latch 27 being passed through said enlarged portion. Finally the ring 51 is formed with a circumferential portion 60 on which normally a pin 61 of the link 37 bears, and with a cam portion 62.

To the cam ring 51 a pin 63 is fixed which projects through a concentric slot made in the annular plate 47 and carries a head 64 for operation of the ring 51 by hand.

The operation of the shutter is as follows:

If it is desired to make a time exposure, the disk 51 is set into the position shown in Fig. 6, in which the disk 13 is in engagement with the toothed segment 10, the latch 27 is released, and the link 37 is retracted from the pin 39. At the beginning of the operation the parts are in the position shown in Fig. 1. The operator forces the plunger 16 outwardly, so that the rod 17 engages the arm 26, thus turning the disk 13 anti-clockwise. The rotary movement imparted to the disk is transmitted to the operating member 9 which thereby opens the shutter. At the end of the outward movement of the plunger 16 the latch 27 gets with its nose 29 into locking engagement with the shoulder 30 of the disk 13. Now the parts are in the positions shown in Fig. 2. As appears from this figure the rod 17 is slightly turned inwardly. Now the plunger 16 is released, and it is forced inwardly and into initial position by the spring 33, and the said spring acting on the disk 23 also sets the rod 17 into the original position and axially of the cylinder 15. Now the shutter is held open by the latch 27 engaging the disk 13. At the end of the desired time of exposure the plunger 16 is again forced outwardly and now it engages the arm 32 of the latch 27, which therefore releases the disk 13 and permits the spring 34 to return the member 9 into initial position and to close the shutter. Finally, the plunger 16 is released, and it is pressed by the spring 33 into the cylinder 15, whereupon the parts are again in the position shown in Fig. 1.

If it is desired to make a ball exposure, the disk 51 is turned anti-clockwise so far that the cam face 57 engages the pin 58 and retracts the latch 27 from the disk 13, while the said disk is still in engagement with the toothed segment 10, and the link 37 is out of engagement with the pin 39. The operator forces the plunger 16 outwardly and thereby opens the shutter, and after the desired time of exposure he releases the plunger 16, so that the disk 13 and the operating member 9 immediately return into initial position for closing the shutter.

If it is desired to make an instantaneous expo-

sure, the ring 51 is further turned anti-clockwise, until the link 37 is released and engages the pin 39, and the disks 13, 46 are released, so that the disk 13 is retracted from the toothed segment 10, and the disk 46 is thrown into engagement with the toothed portion 45 of the pawl 41. The latch 27 is still out of engagement with the disk 27. Now the desired time of exposure is set by means of the retarding mechanism of the motor or master member, and the motor or master member is set by means of the usual setting lever. If the instantaneous exposure is to be made the operator forces the plunger 16 outwardly, whereupon the rod 17 engages the arm 26 and turns the disks 13, 46 anti-clockwise, and by such anti-clockwise movement the pawl 41 is retracted from the motor or master member, which therefore causes instantaneous exposure.

I claim:

1. In a shutter for photographic cameras, the combination, with the blades, an operating member therefor, a motor or master member, and a member controlling the operation of said motor or master member, of a hand operated device, an intermediate member adapted for driving engagement with said blade operating member and said controlling member, and hand operated means for selectively throwing said intermediate member into engagement with said blade operating member and said member controlling the operation of the motor or master member.

2. A shutter as claimed in claim 1, in which said motor or master member is normally out of engagement with said blade operating member, and in which hand operated means are provided for throwing said motor or master member into engagement with said blade operating member.

3. A shutter as claimed in claim 1, in which means are provided for locking said intermediate member in position after operation by said hand operated device, said locking means being in position when in locking position for being thrown out of locking engagement with said intermediate member by said hand-operated device, and in which hand operated means are provided for controlling said locking means.

4. In a shutter for photographic cameras, the combination, with the blades, and an operating member therefor, of a rotary disk in driving engagement with said blade operating member, a hand operated device including a rod adapted for

loose engagement with said disk and for being moved thereby out of its normal position, means tending to return said rod into normal position, a latch adapted to lock said rotary disk in the position into which it has been turned by said hand operated device, said latch being adapted when in locking position to be directly engaged by said hand operated device and to be thrown thereby out of locking engagement with said rotary disk, and hand operated means for setting said latch out of position for locking engagement with said disk.

5. A shutter as claimed in claim 4, comprising in addition a motor or master member, a pawl for locking the same in set position and adapted to be engaged by said disk and to be thrown thereby out of locking engagement with said motor or master member, and hand operated means for selectively setting said disk in position for engagement with said blade operating member and said pawl and for setting said motor or master member into and out of driving engagement with said blade operating member.

6. A shutter as claimed in claim 4, in which the said disk and the latch are each provided with a concave arm in position for engagement with the said rod.

7. A shutter as claimed in claim 4, in which the hand operated device comprises a cylinder, a piston reciprocating therein, a rod formed at its inner end with a disk bearing on said piston, and a spring within said cylinder bearing on said disk and adapted to force the piston inwardly and to hold said disk close on said piston and permitting the disk and its rod to be turned laterally.

8. In a shutter for photographic cameras, the combination, with the blades, and an operating member therefor, of a rotary disk in driving engagement with said blade operating member, a hand operated device including a rod adapted for loose engagement with said disk and for being moved thereby out of its normal position, means tending to return said rod into normal position, and a latch adapted to lock said rotary disk in the position into which it has been turned by said hand operated device, said latch being adapted when in locking position to be directly engaged by said hand operated device and to be thrown thereby out of locking engagement with said rotary disk.
